CLAIM

The ornamental design for a neck of a bottle, as shown and described.

DESCRIPTION

FIG. 1 is a front, left perspective view of a neck of a bottle, showing my new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof;

FIG. 7 is a bottom plan view thereof; and,

FIG. 8 is a cross sectional view thereof, taken along lines 8-8 in FIG. 2.

The broken lines immediately adjacent the shaded areas represent the bounds of the claimed design while all other broken lines illustrate parts of the article; the broken lines form no part of the claimed design.
